DEVICE FOR USE IN WAVING HAIR

Yvonne Worth, East Orange, N. J., assignor, by
mesne assignments, to Zotos Corporation, New
York, N. Y., a corporation of New York

Application January 28, 1933, Serial No. 653,958

17 Claims. (CL 132—36.2)

My present invention has for its object to provide a novel device for use in making so-called permanent hair waving which is particularly adapted for the personal use of and application by the one so desiring to treat their hair in the privacy of the home.

A further object of my invention is to provide a hair steaming and heating device which is made in a flexible form and capable of enveloping a wisp or tress of hair previously wrapped or entwined on a curler and which can be applied with the same facility as that with which the hair is applied to the curler in the first instant.

My invention further comprehends the provision of an article of commerce, adapted for the purpose described which comprises a suitable wrapper to which is applied a package of chemical agents adapted to react to generate heat when moistened and a part composed of absorbent material which when wet performs the double function of furnishing the necessary moisture to cause the chemical action and to provide the desired moisture in the form of vapor for affecting the hair as the result of the heat generated.

To these and other ends my invention consists in further improvements and arrangement of parts all as will be more fully described in the following specification, the novel features being set forth in the appended claims:

In the drawing.

Fig. 1 is a view showing two of the devices embodying my invention as they appear in use and rolled into a substantially cylindrical form.

Fig. 2 is a plan view of the device with the parts opened outwardly.

Fig. 3 is a plan view showing the moistening fabric in operative position over the chemical pad.

Fig. 4 is a side view of the parts looking in the direction indicated by the arrows in Fig. 2.

Fig. 5 is a plan view illustrating the position of the parts when applied to a wisp of hair.

Fig. 6 is a sectional view on the line 6x—6x of Fig. 5.

Fig. 7 is an enlarged cross-sectional view taken on the line 7x—7x of Fig. 1 showing the wrapping step.

Fig. 8 is a cross-sectional view taken on the line 8x—8x of Fig. 3.

Similar reference characters in the several figures represent similar parts.

The present day method of applying permanent waves to women's hair necessitates the use of

cumbersome and expensive apparatus which must be manipulated by an operator. This requires one desiring to have her hair so treated to visit a so-called beauty parlor and be subjected to considerable annoyance with the attendant loss of valuable time in addition to which the expense entailed is considerable.

In carrying out my invention I provide a form of wrapper which constitutes an envelope for the selected strands of hair, which are first wound upon a hair curler, the essential feature of which is the provision of means for supplying automatically the required moisture at a temperature sufficiently high and for a sufficient length of time to effect the required "set" to the individual hairs comprising a selected strand. To this end I employ a wrapper of one or more thicknesses of flexible material which may easily be rolled into cylindrical form in the fingers and mount thereon a chemical pack in the form of a thin package, or envelope containing heat generating chemicals in a dry form with means for readily applying moisture thereto. The wrapper also comprises an inner lining of foil which prevents contact of the chemical package with the hair, and serves as an insulating wall. The latter also assists in retaining the heat and protects the outer portion of the wrapper from absorption of moisture when the device is rolled up and in operation.

In the illustrations the present embodiment of my invention is shown as comprising an exterior flexible covering A preferably of paper which has a good textile strength and in practice I use two thicknesses, indicated by 1 and 2, of a light weight bond paper which are united at one edge 3 as by folding centrally a larger sheet. Overlying the covering A is a sheet of foil B of any suitable metal such as aluminum, the dimensions of which are such that approximately one-half of its area indicated by 4, covers one-half of the outer portion of the wrapper adjacent the fold 3, the remaining portion 5 being adapted to be folded along the line indicated by 6 into an overlapping position as shown in Fig. 5. The part 4 is imperforate and the part 5 is provided with numerous perforations 7 in part of its area. The foil B is attached by a suitable adhesive material, such as rubber cement, to the outer covering A applied in a narrow strip contiguous to the fold lines 3 and 6 as will be understood.

On part of the portion 4 of the foil B, corresponding to and opposite the area containing the perforations 7, I secure a thin flat package 8 containing the requisite quantity of heat gen-

erating chemicals. This package is preferably made of a layer of absorbent paper folded into the form of an envelope and secured in position with the overlapping portions of the paper on the underside.

- 5 Secured in any suitable manner to the parts above described and in such a position that it may be folded over the envelope 8 is a flap 9 of cloth. In practice I prefer to attach this at one edge to the outer layer 2 of the covering A (see 10 Fig. 8) so that when it is in use it will serve to bind the edges of both layers of the covering A and the panel 4 of the foil B together. The flap 9 is of sufficient size to overlap the envelope 8 and is preferably made of canton flannel or the 15 like which will readily hold enough water when immersed to completely dampen the contents of the envelope and also retain a sufficient quantity to supply the desired vapor as part of the heat treatment.
- 20 In order to facilitate an understanding of the method of using the device it should be first explained that where a head of hair is to be curled, or given the so-called permanent wave effect, it is divided into a number of tresses which are 25 wrapped or wound on hair curlers, indicated by C, of any desired or preferred construction and preferably of metal. This may be done before or after shampooing the hair and with or without first treating the hair with a suitable lotion usually 30 employed to effect a softening of the individual hairs and add to the "set" upon the application of heat and moisture. The wisps or tresses of hair at the bottom of the curlers and close to the scalp are surrounded with protectors in the nature of 35 perforated slotted washers D which serve to protect the scalp against the high temperature to which the hair is subsequently subjected.
- In using the device embodying my invention 40 the parts are unfolded or opened to the position shown in Fig. 2 and the cloth tab 9 is dipped in water and then folded over against the face of the envelope 8 as shown in Fig. 3. Next the perforated leaf 5 of the foil B is folded along the line 45 6 causing the perforations 7 to overlap the tab 9 as indicated in Figs. 5 and 6. The operator now places one of the curlers with the hair entwined thereon against the perforated portion of the foil with the marginal edge 10 adjacent, or in contact with, the protective washer and proceeds to wrap or wind the device into cylindrical form. In doing this the overlapping convolutions are compressed against the enclosure and a close 50 union is effected. This is maintained by the outer layers 1 and 2 of the covering A which also serves to retain the heat generated for the required length of time to produce the desired effect or hair treatment. Thereafter the covering is 55 unwound, removed and discarded.
- 60 It will be observed from the illustrations that the fold 3 in the outer covering layers 1 and 2 and the fold 6 in the protecting foil layers B are at the inner side of beginning of the convolutions thus allowing the parts 1 and 5 to slip with reference to the parts 2 and 4 during the winding operation so that the completed cartridge is comparatively smooth and free from wrinkles.
- Various combinations of chemical ingredients 70 may be used as the heat generating unit with which to fill the envelope 8 but in practice I prefer to use a formula which is slow in its heat generation action, requiring from two to three minutes to reach an appreciable temperature thus giving the user ample time to complete the wrapping operation. If desired this may be accom-

plished where the chemical agents employed are comparatively quick in their action by using a less absorbent paper for the envelope 8. Another requirement of said ingredients is that the combination used should be such that the temperature created will within a short period reach approximately 208° F., hold the heat at this point for about four minutes and thereafter rapidly cool. The latter effect may in a large measure be effected by the quantity of the material supplied in the package 8. I have found that a combination of calcium oxide, ammonium chloride, potassium chloride, potassium chlorate and powdered aluminum may be advantageously employed to produce the desired effect and that when mixed in the proper proportions about ten grains will be sufficient for the purposes described. 15

My invention, it will be observed, can be used by professional hair dressers in lieu of the expensive machine equipment now employed for permanent waving of the hair and may with equal 20 facility be used by individuals who may wish to treat their own hair without the assistance of others.

What is claimed is:

1. A hair waving pad comprising an outer layer 25 of non-absorbent material and an inner layer of absorbent material containing an exothermic material.

2. A hair waving pad comprising an outer layer of non-absorbent material and an inner layer in 30 the form of an envelope of absorbent material containing an exothermic material.

3. An article of manufacture comprising superimposed outer and inner flexible sheets, an absorbent packet containing chemical heat generating ingredients placed on the inner sheet and a moisture absorbing sheet in cooperative engagement with said packet. 35

4. An article of manufacture comprising an outer flexible covering sheet, an inner sheet of moisture-resisting and heat-retaining material, a moisture-absorbent packet thereon of chemical ingredients adapted to generate heat and a moisture-absorbing sheet arranged to overlie the 45 packet.

5. An article of manufacture comprising an outer paper wrapping sheet, an inner sheet of metal foil thereon, a moisture-absorbent packet containing ingredients which generate heat upon 50 the application of moisture and an absorbent sheet adapted to be wetted and laid in contact with the packet.

6. A hair waving device comprising a flexible envelope of moisture-absorbing material containing ingredients adapted to generate heat when moistened, and a flexible covering sheet, said envelope and sheet being adapted to be rolled around a wound tress of hair to be waved. 55

7. A hair waving device comprising superimposed layers of paper and metal foil and an absorbent envelope containing ingredients adapted to generate heat when moistened, said paper, foil and envelope forming a unit capable of being wrapped around a curler containing a wisp of 60 hair.

8. In a hair waving device, the combination with a flexible outer covering sheet, a sheet of flexible metal foil overlying one end thereof and a moisture-absorbent container for ingredients 70 which are adapted to generate heat when moistened placed upon the foil, of a piece of absorbent fabric adapted to overlie said container, said several parts being adapted to be placed around a wound tress of hair to be waved. 75

9. An article of manufacture comprising a moisture-absorbent container for ingredients which generate heat when moistened, a flexible covering sheet therefor comprising an underlying imperforate portion and an overlying perforated portion, said sheet and container being adapted to be wrapped around a wound tress of hair to be waved with the perforated portion of the sheet adjacent the tress.
10. An article of manufacture comprising a container of absorbent material containing ingredients which generate heat when moistened, a flexible sheet of waterproof material comprising an imperforate portion underlying the container and a perforated portion overlying it, a layer of absorbent material interposed between said container and said perforated portion and a wrapping sheet of greater area than the first mentioned sheet and attached to the imperforate portion thereof.
11. An article of manufacture comprising a container of absorbent material containing ingredients which generate heat when moistened, a flexible sheet of waterproof material comprising an imperforate portion underlying and attached to the container and a perforated portion adapted to be folded over the container, a wrapping sheet of greater area than the waterproof sheet underlying its imperforate portion and attached thereto, and a piece of absorbent material carried by one of the aforementioned sheets and arranged to contact with said container.
12. An article of manufacture comprising a container of porous paper containing ingredients which generate heat when moistened, a sheet of metal foil having an imperforate portion underlying and attached to the container and a perforated portion adapted to overlie the container, a paper covering sheet attached to and extending beyond the imperforate portion of said foil, and a piece of absorbent material interposed between said container and the perforated portion of the foil.
13. A hair waving pad including a flexible pervious envelope containing an exothermic material and a backing of flexible material.
14. A hair waving pad including a flexible envelope containing an exothermic material, one face of which is pervious, and a backing of flexible material.
15. A hair waving pad comprising a layer of non-porous material, a layer of porous material, and exothermic material between said layers.
16. A hair waving pad adapted to be rolled around a wound tress of hair, comprising an outer wrapper of impervious material, an inner foil backing sheet and an envelope containing an exothermic chemical, the outer wrapper and foil backing sheet being secured together along a line parallel to the longitudinal axis of the wound tress.
17. A hair waving pad comprising an outer wrapper of impervious material, an inner foil backing sheet secured thereto, an envelope containing an exothermic chemical secured to the foil backing sheet, and a sheet of absorbent material secured to the outer wrapper adjacent an edge thereof and adapted to pass around said edge and to overlie said envelope.

YVONNE WORTH.
